HOBBYHORSE HAVING CHANGEABLE GAIT

Ben C. Reynolds and Clayton A. Reynolds,
Kane, Pa.

Application June 9, 1950, Serial No. 166,994

3 Claims. (Cl. 272—53.2)

1

The present invention relates to a hobby horse having changeable gaits and it consists in the combinations, constructions and arrangements of parts herein described and claimed.

Generally, the invention consists of a hobby horse having a relatively large rectangular base upon which is centrally mounted a vertical standard adjacent the upper end of which is pivotally mounted the hollow body of a simulated horse which extends parallel to the horizontal axis of the base. Upon either side of the standard, below the pivot point of the body, there is mounted a segmental gear with each of which is enmeshed a pinion affixed to a shaft protruding inwardly from the adjacent inner side of the body. Also affixed to each of these shafts is a disc. A pair of forelegs is pivotally mounted upon the outer side of the forward end of the body and a pair of hind legs is pivotally mounted upon the outer side of the rear end of the body. An inwardly extending pin is affixed to each of the legs and extends into the interior of the body through an adjacent arcuate slot provided therefor in the body and to each of the pins there is pivotally connected a link whose other end is selectively engaged with one of the discs at various positions adjacent the periphery thereof. Depending upon the points of connection of such links with such discs, a variety of gaits may be simulated by the legs when the body is worked back and forth by a child sitting thereon, as, for example, a trotting gait, a pacing gait and a galloping gait.

It is accordingly an object of the invention to provide a device of the character set forth wherein means is provided for the simulation of various gaits of four-legged animals.

Another object of the invention is the provision of a device of the character set forth which is simple in construction, inexpensive to manufacture and yet efficient and effective in use.

A further object of the invention is to provide a device of the character set forth wherein simple means is provided for changing the type of gait simulated by leg members forming a part of the invention.

A still further object of the invention is the provision of a device of the character set forth which may be readily manufactured of materials which are easily and cheaply obtained.

Another object of the invention is the provision, in a device of the character set forth of novel means for actuating certain leg members forming a part of the invention.

Other and further objects of the invention will become apparent from a reading of the following

2

specification taken in conjunction with the drawings, in which:

Figure 1 is a side elevational view, partly broken away, of an embodiment of the invention.

Figure 2 is a plan view thereof.

Figure 3 is a front elevational view of the device shown in Figures 1 and 2.

Figure 4 is a view similar to Figure 1 but showing the device in one position it may assume while the mechanism therein is connected to simulate a trotting gait.

Figure 5 is a view similar to Figure 4 but showing another position the device may assume while its mechanism is connected to simulate a trotting gait.

Figure 6 is a fragmentary sectional view taken along line 6—6 of Figure 7.

Figure 7 is an enlarged fragmentary sectional view taken along line 7—7 of Figure 1.

Figure 8 is an enlarged fragmentary sectional view taken along line 8—8 of Figure 5.

Figure 9 is a fragmentary sectional view taken along line 9—9 of Figure 10.

Figure 10 is a fragmentary sectional view similar to Figure 8 but showing the mechanism therein connected in such manner as to simulate a galloping gait.

Figure 11 is an elevational view of a body member forming a part of the invention.

Figure 12 is an elevational view of a foreleg member forming a part of the invention.

Figure 13 is an elevational view of a hind leg member forming a part of the invention, and

Figure 14 is an elevational view of a head member forming a part of the invention.

Referring more particularly to the drawings, there is shown therein a hobby horse having a relatively large rectangular base 10 centrally affixed to which is an upright standard 11. Extending laterally through the standard 11 adjacent the upper end thereof is an elongated bolt 12 having a head 13 and provided with a nut 14. The bolt 12 acts to hold together in parallel spaced relation a pair of body members 15, the head 13 being countersunk in the outer side of one of the body members and the nut 14 being received in a recess 16 in the outer side of the other body member.

A filler plate 17 is interposed between the upper ends of the body members and forms in effect a "back" for the simulated animal which is, in the presently illustrated form, a horse.

A head member 18, in this case simulating that of a horse, is interposed between the body members 15, at the forward upper portions thereof and

is provided upon both sides with two bolts 19, extending transversely through the body members 15, holding the head in a fixed position, which if desired, can be changed, in order that the head member 18, be movable, to and fro, upon a pivot.

A bolt 20 extends transversely through the body members 15 adjacent the forward ends thereof and has pivotally mounted at each end thereof a foreleg member 21, each of which is provided with an opening 22 for the reception of such bolt 20. A like bolt 23 extends transversely through the body members 15 adjacent the rear end thereof and has pivotally mounted at either end thereof a rear leg member 24 each of which is provided with an opening 25 for the reception of such bolt 23.

Upon either side of the standard 11 below the bolt 12 there is affixed by means of a bolt 26 or the like, a segmental gear 27. A pinion 28 is enmeshed with each of the segmental gears 27 and each pinion is revolvably mounted upon a shaft 29 which extends laterally inwardly from the lower central portion of each of the body members 15.

Formed integrally with or affixed to each of the pinions 28 is a disc 30.

Each of the forelegs 21 is provided with an inwardly extending pin 31 at a point below the bolt 23 and each pin extends through an arcuate slot 32 formed in the adjacent portion of the body member 15. To the inner end of each of the pins 31 there is pivotally connected one end of a forward link 33, the other end of which is connected to the disc 30 upon its respective side of the hobby horse.

Each of the hind legs 24 is provided with an inwardly extending pin 34 which extends through an arcuate slot 35 formed in the adjacent portion of the body member 15 and has pivotally connected to its inner end a rear link member 36, the other end of which is pivotally connected to the disc 30 upon its respective side of the hobby horse.

The links 33 and 36 are connected with the discs 30 at selective points adjacent the peripheries of such discs by means of pins 37 or the like.

A tail member 38 is mounted between the body members 15 at the upper rear portions thereof and filler panels such as the front panel 39 are interposed between the edge portions of the body members 15 wherever desirable to help complete the simulation of an actual animal.

In operation, it will be apparent that a child using the device may mount upon the back of the hobby horse with or without a saddle and that thereafter a forward and rearward rocking motion of the body members 15 and attached devices, with the bolt 12 supporting the same and acting as a pivot, will cause the pinions 28 to oscillate forwardly and rearwardly at the same time causing the discs 30 to oscillate with respect to their shafts 29. Such action will cause the links 33 and 36 to reciprocate substantially parallel to the horizontal axis of the body members 15 and thus cause an oscillating movement of each of the legs 21 and 24 upon their respective pivots 20 and 23, thus simulating the actual movement of the legs of a live quadruped.

If both of the links 33 are connected to their respective discs 30 in parallel registry to each other and both of the links 36 are likewise connected to their respective discs 30, as shown, for example, in Figures 9 and 10 of the drawings, then both the forelegs 21 will move forwardly simultaneously while both hind legs 24

will move rearwardly together at the same time and, upon completion of such movement, both forelegs 21 will move rearwardly together while both hind legs 23 will move forwardly together and simultaneously with the rearward movement of the forelegs, thus simulating a gallop.

If, on the other hand, the links 33 and 36 on one side of the device are both connected at the same point upon the forward half of their associated disc 30 by a single pin 37 and the other links 33 and 36 are connected to the rearward half of their respective disc 30 likewise by a single pin 37, as shown, for example, in Figure 8 of the drawings, then the resultant movements 10 of the leg members 21 and 23 will be those of a trotting gait, as illustrated in Figures 4 and 5.

It will be apparent that by selectively connecting the links 33 and 36 to their respective discs 30, other well known gaits, such as the 20 pacer gait, may be simulated by the leg members 21 and 23 when the device is rocked upon the bolt 12, as aforesaid.

While but one form of the invention has been 25 shown and described herein, it will be readily apparent to those skilled in the art that many minor modifications may be made without departing from the spirit of the invention or the scope of the appended claims.

What is claimed is:

30 1. A device of the character described comprising a base, a standard centrally affixed to said base, a hollow body receiving and pivotally connected to said standard adjacent the upper end thereof, a foreleg pivoted to either side of the forward portion of said body, a hind leg pivoted to either side of the rear portion of said body, and means interconnecting the standard and the body for imparting oscillating movement to said legs relative to said body when said body is oscillated with respect to said standard, said means including a segmental gear affixed to each side of said standard within said body, a shaft extending inwardly from each side of said body, a pinion revolvably mounted upon each shaft and enmeshed with a segmental gear, a disc affixed to each of said pinions and likewise revolvable upon its associated shaft, a pin extending inwardly from each leg through said body, and a link interconnecting each pin upon each side of the body with the disc adjacent that side of the body.

2. A device of the character described comprising a base, a standard centrally affixed to said base, a hollow body receiving and pivotally connected to said standard adjacent the upper end thereof, a foreleg pivoted to either side of the forward portion of said body, a hind leg pivoted to either side of the rear portion of said body, and means interconnecting the standard and the body for imparting oscillating movement to said legs relative to said body when said body is oscillated with respect to said standard, said means including a segmental gear affixed to each side of said standard within said body, a shaft extending inwardly from each side of said body, a pinion revolvably mounted upon each shaft and enmeshed with a segmental gear, a disc affixed to each of said pinions and likewise revolvable upon its associated shaft, a pin extending inwardly from each leg through said body, and a link interconnecting each pin upon each side of the body with the disc adjacent that side of the body and said last mentioned means including pins for selectively connecting said links to various points

adjacent the peripheries of the discs associated with said links.

3. A device of the character described comprising a base, a standard centrally affixed to said base, a hollow body receiving and pivotally connected to said standard adjacent the upper end thereof, a foreleg pivoted to either side of the forward portion of said body, a hind leg pivoted to either side of the rear portion of said body, and means interconnecting the standard and the body for imparting oscillating movement to said legs relative to said body when said body is oscillated with respect to said standard, said means including a segmental gear affixed to each side of said standard within said body, a shaft extending inwardly from each side of said body, a pinion revolvably mounted upon each shaft and enmeshed with a segmental gear, a disc affixed to each of said pinions and likewise revolvably upon its associated shaft, a pin extending inwardly from each leg through said body, and a link inter-

connecting each pin upon each side of the body with the disc adjacent that side of the body, said body being provided with an arcuate slot adjacent each pin for the reception of said pin.
